(57) **CLAIM**

The ornamental design for chewable product, as shown and described.

DESCRIPTION

FIG. 1 is a perspective view of the chewable product showing my new design;

FIG. 2 is a top plan view thereof;

FIG. 3 is a right side view thereof;

FIG. 4 is a left side view thereof;

FIG. 5 is a rear view thereof; and,

FIG. 6 is a front view thereof.

The phantom lines immediately adjacent the shaded areas represent the bounds of the claim and all other phantom lines are for illustrative purposes only. None of the phantom lines form a part of the claimed design.
